UNITED STATES PATENT OFFICE.

CLARENCE ELMER FREY, OF LINCOLN, NEBRASKA.

MEDICAL APPLICATOR.

Application filed August 17, 1926. Serial No. 129,753.

The object of the invention is to provide a medical instrument particularly adapted for gynecological use and the self-application by the patient of a medicament to the affected part, particularly in a cavity of the body; to provide an instrument which may be readily charged with a prescribed or definite dose of a medicament, so that after application it may be known that the desired dose reached the affected part; to provide an instrument in which, after charging, the dose may be carried without loss so that it may be applied at any subsequent time, as when the patient is traveling; and to provide an instrument in which the construction is of simple and yet effective form and therefore susceptible of cheap manufacture and low marketing cost.

With this object in view, the invention consists in a construction and combination of parts of which a preferred embodiment is illustrated in the accompanying drawings, wherein:

Figure 1 is a side elevational view of the invention with the plunger partly retracted.

Figure 2 is a view similar to Figure 1 but with the plunger fully retracted and the cap swung to open position, a collapsible tube being shown attached in the operation of charging.

Figure 3 is a view similar to Figure 2 showing the plunger withdrawn and the cap in open position with a supplemental cap attached, as when the device is ready for transportation after charging.

Figure 4 is a central vertical sectional view on the plane indicated by the line 4—4 of Figure 1.

Figure 5 is a top plan view of the structure of Figure 1.

Designed particularly for the application of a definite dose of a medicament to inaccessible parts and particularly to the cervix uteri, the invention comprises the barrel 10 formed at the mouth or discharge end with a spherical enlargement 11 for the distention of the parts, the discharge mouth of the barrel being provided with a removable closure 12, preferably, as illustrated, a screw with a knurled head, so that the closure may be readily attached and detached. The barrel at the remote or charging end is similarly enlarged, as indicated at 13, this rear enlarge-

ment being internally threaded, as at 14, for the reception alternately of a discharge 55 mouth 15 of a collapsible tube 16 or a supplemental closure cap 17.

A swinging cap 18 is hingedly connected with the enlargement 13 at the rear end exteriorly of the latter, the pivot point of the hinge being offset, as at 19, so that the cap may be swung to one side of the barrel. The cap 18 acts as a guide for the staff 20 of the plunger 21, the latter fitting snugly the bore of the barrel and the staff at the upper end being 65 provided with a knob 22.

When the plunger is fully retracted, it enters a counterbore 23 in the swinging cap and the latter and the plunger and staff may be swung laterally so that the supplemental cap 70 will expose the charging end of the barrel and the plunger staff lie parallel with the barrel. The coupling of the collapsible tube with the barrel prior to the attachment of the closure 12 will permit the full charging 75 of the barrel and after the disconnection of the flexible tube, the supplemental cap 17 may be applied and the instrument and charge carried until it is desired to use the contained dose. Thereafter the removal of 80 the supplemental cap 17 and the swinging of the cap 18 into its position of closure over the rear end of the barrel will position the plunger in alignment with the barrel and its movement forward will serve to eject the 85 contained charge or dose after the removal of the closure 12, the operation of moving the plunger forward, of course, following the insertion of the barrel.

The invention having been described, what 90 is claimed as new and useful is:

A medical applicator comprising a barrel, a cap swingingly connected with the barrel at the end remote from the discharge mouth, and a plunger snugly fitting the bore of the 95 barrel and provided with a staff extending through and guided by said cap, the cap and plunger staff being swingable into a position in parallelism with the barrel or into a position where the staff is axially aligned with 100 the bore of the barrel, the staff, when the plunger is engaged in the bore of the barrel, retaining the cap in closed position.

In testimony whereof he affixes his signature.

CLARENCE E. FREY.
